ROTARY CAN OPENER

Robert E. McLean, Fort Benning, Ga.

Application April 7, 1944, Serial No. 529,974

15 Claims.

(Cl. 30—15)

This invention relates generally to the class of can openers and pertains particularly to improvements in can openers of the rotary type.

A principal object of the present invention is to provide an improved rotary type can opener having an oscillatable knife carrying head, with a novel gear coupling means between the head and a driving handle or crank wherein automatic release of the connection between the driving handle and knife carrying head is effected when the head has been oscillated to working position, whereby continual turning or rotation of the handle may then be carried on for the turning of a driving wheel which has driving connection with the can, to effect the turning of the can with respect to the knife and the cutting out of the can head.

Another object of the invention is to provide an improved rotary type can opener having an oscillatable knife carrying head, with a novel gear coupling means between the head and a driving handle or crank wherein automatic re-engagement of the connection between the driving handle and knife carrying head is effected, after the head has been oscillated to working position and connection released to provide for continual clockwise turning or rotation of the handle, to release the can from the device and prepare the device for reception of the next can.

Still another object of the invention is to provide an improved rotary type can opener having the above described features, which is compact, exceptionally easy to operate and inexpensive to manufacture.

Other advantages of the invention will become apparent as the description of the same proceeds and the invention will be best understood from a consideration of the following detailed description taken in association with the accompanying drawings forming a part of this specification, with the understanding that minor changes may be made in the invention so long as such changes mark no material departure from the salient features of the invention as expressed in the appended claims.

In the drawings:

Figure 1 is a view in elevation of the right hand or handle side of one embodiment of the present invention, the handle being removed.

Figure 2 is a view in elevation of the can side or left side of the device shown in Figure 1.

Figure 3 is a top plan view of the same.

Figure 4 is a vertical central section taken substantially upon the line 4—4 of Figure 1.

Figure 5 illustrates the application of the em-

bodiment of the invention of the foregoing figures as applied to a wall bracket and operated by a crank type handle.

Figure 6 is a vertical longitudinal section through another embodiment of the invention, the section being substantially upon the line 6—6 of Figure 7.

Figure 7 is a view in elevation of the left hand side of the second embodiment.

Referring now more particularly to the drawings it will be noticed upon reference to my prior application Ser. No. 518,760, filed Jan. 18, 1944, that the opener of the present invention is somewhat similar in operation to that illustrated in Figures 11 to 16 of such application. The principal difference in construction lies in the means for positively effecting the clockwise and counter-clockwise turning of the knife carrying head.

The embodiment of the invention as illustrated in Figures 1 to 4 is the same as that illustrated in Figure 5 but in the first mentioned figures the device is designed to be held in the hand for application to a can while in Figure 5 it is shown mounted upon a supporting bracket which may be attached to a wall or other suitable support.

The body plate for the embodiment shown in Figures 1 to 4 inclusive is generally designated 10 and this plate has at its bottom end the laterally extending can guard flange 11 while its top end is flat part-way across from the forward edge is indicated at 12 and rounded toward the back edge as indicated at 13.

Formed integrally with the front and rear edges of the body plate 10 are the can engaging fingers 14 and 15 respectively. These fingers cooperate with the can guard flange 11 to maintain the body in the proper position upon a can, the flange 11 abutting the side wall of the can while the fingers 14 and 15 engage across the top edge thereof.

Overlying the top of the body plate 10 is a head member which is generally designated 16. This head is substantially U shaped and comprises the flat spaced parallel portions 17 and 18 which are connected by the intermediate yoke portion 19.

Threaded in the body plate 10 to extend from the side thereof opposite from the can guard 11, is a pivot screw 20 which has the portion of small diameter at its end as indicated at 21, which is threaded into a suitable threaded aperture in the body 10, and between this portion 21 and the head, is divided into the two bearing portions 22 and 23.

The side 17 of the U shaped head 16 lies upon the outer side of the body plate 10 remote from

the guard 11 and is oscillatably mounted upon the intermediate bearing portion 22 as is clearly shown in Figure 4. The yoke portion 19 of the head lies relatively close to the top edge 12 of the body so that the oscillation of the head counter-clockwise is limited to a vertical position through the engagement of the yoke with the top edge of the body. Oscillation clockwise of the head to a predetermined extent, is permitted by reason of the curved edge portion 13 of the body plate.

Upon the inner side of the side portion 18 of the head is located the cutter 24 which is secured in position by means of screws 25 or in any other suitable manner. However, if desired, this cutter may be formed as an integral part of the side portion 18, therefore it is to be understood that such construction is contemplated in defining the implement as comprising an oscillatable head and a cutter carried thereby.

The numeral 26 designates a gear sector plate which is provided with a bearing opening 27 to receive the bearing portion 23 of the pivot or bearing screw 20. This plate 26 thus lies upon the side of the head portion 17 opposite from the body plate 10 and is designed to have rocking movement upon the screw 20 relative to the head.

The rocking movement of the plate 26 relative to the head is limited by the forward and rearward stop wings 28 and 29 which form integral continuation of the top flange 30 and which overlie adjacent edges of the head portion 17 as shown in Figures 2 and 4.

Formed integrally with the plate 26 at the bottom rear corner is the gear sector 31 which, when the head is in upright or fully operative position lies to the rear of the longitudinal center of the implement, as shown in Figure 1.

Upon the longitudinal center of the body plate below the bearing screw 20 there is formed a bearing or journal opening 31b through which extends the shaft 32.

In the form of the invention illustrated in Figures 1 to 4 inclusive, this shaft 32 is formed integrally with a thumb and finger handle 33 but in the bracket mounted or supported form of the invention shown in Figure 5 the shaft, designated 32a, has attached thereto a crank arm or handle 33a.

Also in the form of the invention shown in Figure 5, the body plate is designated 10a and is secured by rivets 34 to a bracket arm 35 which may be mounted upon or secured to a wall or any other suitable support. Except for these differences the implement shown in Figure 5 is of the same design as shown in Figures 1 to 4 inclusive.

The shaft 32 is of reduced size from its free end through the major portion of its length whereby there is formed the shoulder 36. Secured to the reduced portion of the shaft is a gear pinion 37 which is adjacent to the shoulder 36, a toothed driving wheel 38 which is upon the opposite side of the body plate from the gear pinion 37 and at the free end of the shaft, and the journal 39 which is positioned within the bearing opening 31b of the body plate as shown in Figure 4.

The gear pinion 37 is in the plane of the gear sector plate 26 and is adapted for operative coupling with this sector to effect the clockwise turning of the knife carrying head 16, for the purpose of oscillating the knife to inoperative position or what may better be termed the full release position.

The driving wheel 38 lies inside the knife or cutter 24 or between the cutter and the body plate, the toothed periphery of the driving wheel

overlapping the lower end edge of the knife and lying in close proximity to the inner face thereof as is clearly shown in Figure 4.

Mounted upon the shaft 32 at each end of the journal sleeve 39 is a thrust washer 40. These washers maintain the gear pinion and the driving wheel in properly spaced relation with respect to the body plate and the journal, as will be readily apparent.

10 In the form of the invention as illustrated in Figures 6 and 7, the gear sector plate is designated 26a and lies between a portion of the head which is designated 16a, and the body plate 10b.

15 The head 16a has the horizontal yoke portion 19a which at one end is connected with the depending side portion 17a while at its other end it is joined to the upstanding side portion 18a. This upstanding side portion 18a of the head has secured thereto, by means of the securing elements 25a, the cutter 24a.

Extending through the upper end of the body plate 10b, is the pivot shaft 22a, upon which is mounted at its ends, the journals 41 and 42.

The journal 42 is of slightly smaller diameter at its outer end than at its inner end and the outer end of the journal extends through a suitable bearing aperture 43 in a side portion 17a of the head while the larger inner end portion of the journal is positioned in a suitable bearing aperture 44 in the gear sector plate 26a. These two portions of the journal 42 are of a length slightly greater than the width of the plates through which they extend so that these parts are maintained suitably spaced for free oscillatory movement upon the journal.

30 The sector plate in addition to having the gear sector 31a formed integrally therewith, carries the upstanding stop wings 28a and 29a which correspond to the wings 28 and 29 of the first described embodiment. These stops or wings extend upwardly a sufficient distance to engage against the adjacent edges of the intermediate or yoke portion 19a of the head after a slight oscillation of the sector plate has taken place, so as to force the head and the cutter carried thereby to turn with the sector plate.

As in the case of the first described embodiment, the cutter 24a may, instead of being a separate unit from the head, be formed as an integral part thereof, in which case, it would not extend above the yoke portion 19a as it is now illustrated.

55 The cutter 24a is provided with a bearing opening 45 in which is engaged the reduced outer end portion of the journal 41. This connection between the cutter and the journal permits the cutter to be forced away from the driving wheel, when necessary, such as when passing the seam of the can, when the driving wheel, here designated 38a, is in driving connection with the can rim. The head 16a is constructed to have sufficient resiliency to permit such lateral movement of the cutter.

60 The numeral 32b designates the shaft for the driving handle, a portion only of which is illustrated, the same being designated 33b.

65 This shaft, like the shaft 32, has a shoulder 36a and has secured thereto a gear pinion 37a which is adjacent to the shoulder, and the journal sleeve 39a which lies in the bearing opening of the body plate 10b as shown in Figure 6. This journal sleeve forms the separating means between the gear pinion 37a and the driving wheel 38a, the journal being of a length slightly greater than the thickness of the plate 10b so as to ex-

tend beyond the opposite sides thereof as illustrated.

Like the body plate 10, the plate 10b has a can guard 11b at its lower end and the can rim engaging fingers 14a and 15a.

In the operation of the device, reference being had particularly to the embodiment as illustrated in Figures 1 to 4 inclusive, although it will be readily apparent that the description applies to Figures 5 to 7 inclusive, if the head 16 is not in the full release, or extreme clockwise, position, as shown in Figure 5, the operating handle, 33, 33a, or 33b, is rotated counter-clockwise until the head is in such position. If desired, the device may be so constructed that no portion of the lower end of the cutter blade 24 or 24a, protrudes beneath the horizontal plane of the lower edges of the fingers 14 and 15, or 14a and 15a, when the head is in the extreme clockwise position. The device is then placed on the rim or flange of the can so that the fingers rest thereon and the can guard and the inner and upper edge of the driving wheel 38 are against the side of the can, not shown. While held in this position the handle 33 is rotated clockwise. Inasmuch as the teeth of the gear pinion 37 are in mesh with the teeth of the gear sector 31, such clockwise rotation of the gear pinion will cause the plate 26 to oscillate counter-clockwise on its pivot screw or pin 20 until the plate arrives at approximately the position illustrated in Figure 1. It will be seen that when the plate 26 has arrived at this position, further counter-clockwise rotation of the head 16 on its pivot screw or pin 20, is prevented by engagement of the horizontal portion or yoke 19 of the head with the forward part of horizontal top edge 12 of the upper end of the body plate 10.

It will be seen that the head 16 was caused to rotate counter-clockwise by engagement thereof with the turned over portion or wing 29 at the rear of the plate or flange 30 which forms a part of the plate 26. During this oscillation of the head 16 the point of the cutter blade 24 pierced the end of the can.

Further clockwise rotation of the handle 33 feeds the can through the device so that the cutter blade cuts the end or head from the can.

The end of the cutter blade is sufficiently blunt to assure positive traction of the driving wheel 38 with the rim or flange of the can and the head 16 has sufficient resiliency to permit the cutter blade to be forced away from the driving wheel 38 a predetermined amount when necessary, such as when passing the seam of a can.

The weight of the portion of the plate 26 to the rear of the axis of its pivot screw or pin 20, is sufficiently greater than that of the front part or the part forwardly of said axis, to cause the plate to tend to rotate clockwise, by gravity, on its pivot screw when in the position illustrated in Figure 1. This causes the trailing tooth of the gear sector 31 to fall back into engagement with the teeth of the gear pinion 37.

It will be noted that this plate 26 is free to oscillate sufficiently clockwise on its pivot screw or pin 20, to so engage the teeth of the gear pinion 37 before the forward wing 28 of the plate 26 engages the head 16. Thus, on counter-clockwise rotation of the gear pinion 37 the trailing tooth of the gear sector 31 will be inmeshed with a tooth of the gear pinion before the forward wing 28 engages the head 16. Counter-clockwise rotation of the handle will then cause the head to rotate clockwise on its pivot screw until further

oscillation is prevented by the engagement of the head with the body plate 10, or the released position, as shown in Figure 5. If gravity should fail at any time to cause the trailing tooth of the gear sector to engage with the tooth of the gear pinion when the handle is rotated counter-clockwise, such engagement may be positively effected by the application of a slight pressure on the top of the plate 26 at its rear.

10 It will be readily apparent that, whereas the gear sector plate of the embodiment illustrated in Figures 6 and 7 is housed between one side portion of the head 16a and the body plate 10b, the operation of this embodiment is exactly the same as the embodiment illustrated in Figures 1 to 5 inclusive and that the upstanding front and rear wings 28a and 29a function in the same manner as the depending wing portions 28 and 29 of the plate 26. If the application of manual pressure to the rear of the gear sector plate 26a is required, in the event that the plate fails to oscillate under the action of gravity, it will be readily apparent that the necessary slight pressure to cause such oscillation, may be applied to the top of the wing 29a by a finger of one hand while the handle 33b is being turned counter-clockwise by the other hand.

As previously noted the opener of the present invention is compact, exceptionally easy to operate and inexpensive to manufacture. It will also be seen that complete counter-clockwise oscillation of the cutter blade is positive in relation to a relative turning of the operating handle, thus assuring positive penetration of the end or head of the can by the cutter blade when the handle is rotated, and without any effort or action on the part of the operator other than the turning of the handle. Likewise, it will be noted that complete clockwise oscillation of the cutter blade is positive in relation to a relative turning of the handle, thus assuring positive return of the cutter blade to full release position when the handle is rotated, and without any effort on the part of the operator other than the turning of the handle.

50 In practice the radius of the gear pinion 37 and the radius of the gear sector 31 would be such as to provide for the easiest piercing of the end of the can by the point of the cutter blade.

I claim:

1. A rotary can opener comprising, a body member, a head oscillatably supported thereon, a can top cutting knife carried by the head, a shaft rotatably supported on the body, means for turning the shaft, a can rim engaging driving wheel carried by the shaft adjacent to the knife for coaction with the knife, a gear and sector coupling between the shaft and the head for effecting oscillation of the head and the knife to operative or inoperative position by clockwise or counter-clockwise turning of the shaft, and said sector being constructed and arranged to disengage from the gear upon turning the shaft in one direction a predetermined extent for oscillation of the head and knife to fully operative position, whereby continued turning of the shaft may be maintained.

60 2. A rotary can opener as set forth in claim 1, with means for effecting reengagement of the gear and sector to oscillate the head and knife to release or inoperative position upon turning the shaft in the opposite direction.

3. A rotary can opener comprising, a flat body plate, the plate being disposed adjacent to a side

of a can in the use of the opener, a guard flange carried by the plate at one end, a pair of can rim engaging fingers carried by the plate at opposite sides thereof and spaced from said flange, a head member supported on the plate for oscillation upon an axis passing transversely therethrough in a plane extending longitudinally of the plate between said fingers, a can top cutting knife carried by the head in spaced relation with the body plate, a shaft rotatably supported by the body plate for turning on an axis paralleling the oscillation axis for the head, means for turning the shaft, a can flange engaging driving wheel carried by the shaft adjacent to and for cooperation with the can top cutting knife for turning the can relative to the knife, and a gear and sector coupling between the shaft and the head, the sector being constructed and arranged to disengage from the gear upon turning the shaft to a predetermined extent to oscillate the head and knife to operative position, whereby continued free rotation of the shaft may be maintained.

4. A rotary can opener comprising, a body plate which is disposed at a side of a can in the use of the opener, means carried by the plate for engagement with the can at the edge of the top for maintaining the body plate in applied position, that edge of the body plate which is positioned adjacent to the can edge constituting the top, a pivot member secured to and extending transversely of the longitudinal center of the body plate adjacent the top thereof, a head oscillatably supported upon the pivot member, a can top cutting knife carried by the head and disposed in spaced relation with the body plate for oscillation relative to the can top when the body plate is in applied position, a shaft rotatably supported by and extending through the body plate below and parallel with the oscillation axis of said head, a can rim engaging driving wheel carried by the shaft and disposed adjacent to the cutting blade for coaction therewith, a rock plate oscillatably supported upon the pivot member for coaxial oscillation with the head, means for establishing a loose connection between the rock plate and the head, a gear pinion carried by the shaft to be turned thereby, a gear sector carried by the last mentioned plate, the gear sector being constructed and arranged for operative connection with the gear pinion and to disengage from the pinion upon oscillation of the head and the knife to operative position upon turning the shaft a predetermined extent in one direction, whereby continued turning of the shaft may be accomplished, and means for effecting reengagement of the sector with the pinion upon turning the shaft in the opposite direction.

5. A rotary can opener comprising, a body plate, a pivot member secured to the body plate, a can head cutting knife oscillatably supported upon the pivot member for movement in a plane paralleling a side of the body plate, a shaft extending through and rotatably supported by the body plate in spaced parallel relation with the pivot member, a can rim engaging driving wheel secured to the shaft and having its periphery adjacent to the knife for coaction therewith to effect the turning of a can relative to the knife, a rock plate oscillatably supported on the pivot member, means for establishing an operative connection between the rock plate and the knife upon oscillation of the rock plate in either direction upon the pivot member, means for turn-

ing said shaft, and means for establishing a driving connection between the shaft and the rock plate upon the turning of the shaft in either of two directions to effect the oscillation of the knife into operative or inoperative position, the said driving means being so constructed and arranged that upon oscillation of the rock plate and knife into the operative position for the knife the driving connection between the shaft and rock plate will be disestablished.

6. A can opener as set forth in claim 5, in which said driving connection comprises a gear pinion carried by the shaft, and a gear sector carried by the rock plate.

7. A rotary can opener comprising, a body plate, a pivot member carried by the body plate, a head member oscillatably supported upon the pivot member, a can head cutting knife carried by the head member in spaced parallel relation with a side of the body plate, a shaft extending through and rotatably supported by the body plate in spaced parallel relation with the pivot member, a can rim engaging driving wheel carried by the shaft adjacent to said knife for coaction therewith to turn a can relative to the knife, means for turning said shaft, a rock plate oscillatably supported upon the pivot member, spaced wings carried by the rock plate and between which a portion of said head is positioned whereby oscillation of the rock plate in either direction will establish a driving connection between the rock plate and the head, and means for establishing a driving connection between the shaft and the rock plate to effect oscillation of the rock plate and the head upon turning the shaft in either direction, said driving means being so constructed and arranged that the said driving connection will be disestablished after the rock plate and head have reached a predetermined position upon the turning of the shaft in one direction.

8. A rotary can opener as set forth in claim 7, in which the said driving connection between the rock plate and the shaft comprises a pinion gear carried by the shaft, and a gear sector carried by the rock plate.

9. A rotary can opener as set forth in claim 7, in which the said driving connection comprises a gear pinion carried by the shaft and a gear sector carried by the rock plate, and means for over-balancing the rock plate to effect the automatic connection of the gear and sector upon the turning of the shaft in the opposite direction.

10. A rotary can opener comprising, a plate body, a pivot member carried by and extending perpendicular to a side face of the plate body, a head having two angularly related portions, one of said portions being disposed in parallel relation with a side of the plate body and traversed by said pivot member for oscillation thereon, the other portion extending across the top edge of the plate body, a can end cutting knife carried by the said other portion of the head in spaced parallel relation with the plate body, a shaft extending through and rotatably supported by the plate body in spaced parallel relation with the pivot member, a can flange engaging driving wheel carried by the shaft adjacent to and for coaction with said knife to effect the turning of a can relative to the knife, a rock plate oscillatably supported upon the pivot member, a pair of spaced wings carried by the rock plate and between which said head positions, said wings

being selectively operatively coupled with the head upon slight free oscillation of the rock plate whereby the rock plate, head and knife oscillate as a unit to move the knife into and out of operative position with respect to a can head, and means for establishing a driving coupling between said shaft and the rock plate upon the turning of the shaft in either direction, said coupling means being so constructed and arranged that upon the turning of the shaft to a predetermined extent in one direction to oscillate the knife into operative position, the said driving coupling will be broken to permit continued free turning of the shaft and said driving wheel.

11. A rotary can opener as set forth in claim 10, in which the said driving means comprises a gear pinion upon said shaft and a gear sector carried by the rock plate.

12. A rotary can opener as set forth in claim 10, in which the said head and knife together form a substantially U shaped structure within which a major portion of the body plate is enclosed, the said other portion of the head lying in relatively close relation to an edge of the body plate and said body plate edge functioning to limit the oscillation of the head beyond the position where the knife is in operative position.

13. A rotary can opener as set forth in claim 10, in which the said one portion of the head is interposed between the body plate and the rock plate and the said spaced wings form angular extensions of opposite edges of the rock plate, each of said extensions lying across a side edge of the said one portion of the head.

14. A rotary can opener as set forth in claim 10, in which the said rock plate is interposed between the body plate and the said one portion of the head, and said spaced wings form upward extensions of the rock plate and each extension lies across the said other portion of the head.

15. A rotary can opener as set forth in claim 10, in which the said head is in the form of a substantially U shaped body of which the knife forms one side in spaced parallel relation with the said one portion of the head, and the said pivot member extends through both the knife 20 and the said one portion of the head, and a journal supported upon the pivot member and engaging in a bearing aperture in the knife, said knife having movement upon the journal relative to the said flange engaging driving wheel.

25 ROBERT E. MCLEAN.
